DESIGN FOR A RING

Belmiro Pereira, New York, N. Y.

Application December 10, 1942, Serial No. 109,000

Term of patent 7 years

To all whom it may concern:

Be it known that I, Belmiro Pereira, a citizen of the United States of America, residing in New York city, county of New York, and State of New York, have invented a new, original, and ornamental Design for a Ring, of which the following is a specification, reference being had to the accompanying drawing, forming part thereof.

Fig. 1 is a plan view of a ring showing my new design.

Fig. 2 is an edge view thereof.
The dominant feature of my design resides in the portions shown in solid lines.

I claim:
The ornamental design for a ring, substantially as shown and described.

BELMIRO PEREIRA.
